UNITED STATES PATENT OFFICE.

HENRY F. MERKER, OF GRANITE CITY, ILLINOIS, ASSIGNOR OF ONE-HALF TO WILL B. WILLIS, OF EAST ST. LOUIS, ILLINOIS.

RAILWAY RAIL.

Application filed May 13, 1921. Serial No. 469,335.

To all whom it may concern:

Be it known that I, HENRY F. MERKER, a citizen of the United States of America, and a resident of Granite City, in the county of 5 Madison, and State of Illinois, have invented certain new and useful Improvements in Railway Rails, of which the following is a full, clear, and exact description, reference being had to the accompanying drawings, 10 forming a part of this specification.

This invention relates to improvements in railway rails, one of the objects being to provide a duplex rail, or twin rail, consisting of a pair of simple rail sections adapted to be 15 readily rolled, and having their several elements combined with each other to produce a very strong rail structure.

A further object is to produce a rail of this kind comprising two interlocking rail 20 sections combined with each other in such a manner that a load on either section will be effectively distributed to both sections. Each rail section is thus reinforced by the other to avoid the strain which would otherwise result 25 from transmission of the load to only one section. The heads of the different sections are preferably juxtaposed at the longitudinal center line of the rail to provide a tread surface substantially continuous across 30 the top of the sectional rail, whereby the load supported at the center line of the rail is transmitted through the webs of both rail sections.

Another object is to retain the mating 35 rail sections in firm engagement with each other, and I have shown a rail in which the load tends to force the rail sections into engagement with each other, at the same time forcing the side margins of the rail flanges 40 into firm engagement with abutments on the tie plate. This avoids looseness at the rail sections and prevents them from rocking or creeping on the ties. Furthermore, the rail sections firmly engaged with each other at 45 their interlocking faces are better adapted to support the load to which they are subjected.

With the foregoing and other objects in view, the invention comprises the novel construction, combination and arrangement of 50 parts hereinafter more specifically described and illustrated in the accompanying drawings wherein is shown the preferred embodiment of the invention. However, it is to be understood that the invention comprehends 55 changes, variations and modifications which

come within the scope of the claims hereunto appended.

Fig. I is a top view on a small scale showing a rail embodying the features of this invention.

60

Fig. II is a side elevation of the rail.

Fig. III is an enlarged transverse section.

A and B respectively designate mating rail sections adapted to be supported on tie- 65 plates C, the latter being mounted on ties D and secured thereto by means of spikes E. To form a continuous rail, the rail sections A and B are interlocked with each other, as will be hereafter described, and each rail section A is interposed between similar sections 70 A, while each rail section B lies between similar sections B. The rail sections are staggered, as shown by Fig. I, the meeting ends of the rail sections A being separated from the meeting ends of sections B.

75

Each rail section A is provided with a head 1, a base flange 2 and a vertical web 3 uniting said head and base flange. Each rail section B is likewise provided with a head 4, a base flange 5 and a web 6 uniting 80 the same. The heads 1 and 4 are located very close to each other at the longitudinal center line of the rail, so as to provide a wheel receiving surface substantially continuous across the top of the sectional rail. The top faces of the rail sections are 85 preferably inclined downwardly at opposite sides of the center line of the rail (Fig. III) so that a wheel rolling over the sectional rail will engage the same on a line about midway 90 between the side faces of the large head produced by the head members 1 and 4. An ordinary wheel will usually engage both heads 4 at the same time, so the load transmitted from an ordinary wheel will be effectively 95 transmitted through the webs 3 and 6 of both rail sections.

90

The head 4 is extended to provide a longitudinal rib 7, and the head 1 is extended over and seated upon this rib 7. The base 100 flange 2 of each rail section A is extended as shown at 2' in Fig. III, so as to provide a longitudinal rib, and the lower portion of each web 6 is provided with a longitudinal rib 8 seated on the base flange 105 2. The top face of the rib 7 is inclined, and the bottom face of rib 8 is also inclined, as shown by Fig. III, so when the rail sections are forced toward each other these inclined faces on the rail section B will be firmly en- 110

gaged with and wedged between the corresponding inclines on the rail section A.

The base flanges 2 and 5 are extended outwardly from the webs of the respective rail sections, and the outer margins of these base flanges are seated upon the supporting plates C, said base flanges being otherwise separated from the supporting plates, as shown by Fig. III. To accomplish this, the bottom 10 faces of the base flanges may be inclined outwardly and downwardly from the inner edges of the rail sections, and the supporting plate C may have a flat top face on which the outer margins of the base flanges are 15 seated. These base flanges are confined between abutments 10 and 11, preferably formed integral with the supporting plate C. The outer edge of the base flange 5 is engaged with the inner face of the abut- 20 ment 10, while the outer margin of base flange 2 is engaged with the abutment 11, the latter being in the form of a flange extended over the base flange 2 so as to form a groove in which said base flange is seated.

25 Angle bars 12 bridge the spaces between the meeting ends of the rail sections, each angle bar being connected to the adjoining ends of two rail sections and engaged with the heads and flanges of the connected rail 30 sections. Fig. III shows that the top face of angle bar 12 engages the bottom of the head 1, while the lower edge of said bar 12 is provided with a flange conforming to and seated on the base flange 2. The angle bars 35 12 are secured by means of bolts 13 passing through the webs of the rail sections A and B and provided with nuts 14. As shown by Figs. II and III, each bolt 13 passes through a bar 15 on the web 6 and also 40 through a sheet metal locking member 17 on the outer face of said bar, one edge of said locking member being bent over an edge of the bar, and the other edge of the locking member being bent to engage a nut 14. 45 From the foregoing it will be understood that the load is transmitted from a wheel rolling on one or both of the heads 1 and 4 (Fig. III) which are located so close to each other that they form a substantially 50 continuous tread surface corresponding to the top of an ordinary single rail. Since the bottom faces of the base flanges 2 and 5 are separated from the top face of the tie plate C, as shown in Fig. III, the load 55 will force the outer margins of the base flanges into firm engagement with the non- yielding abutments 10 and 11, and this will also tend to force the rail sections into firm engagement with each other, especially at 60 the interlocking faces of the rail sections. The inclined interlocking elements of the sectional rail are thus firmly engaged with each other while the adjacent side faces of the rail sections are otherwise separated 65 from each other to permit firm engagement

at the inclined faces, and at the same time the base flanges 2 and 5 are engaged with stationary supporting plate C so as to prevent rocking of the rail. This firm engagement of the base flanges with the plate C 70 also tends to prevent creepage of the sectional rail.

Under some conditions, a wheel will rest entirely upon only one of the heads 1 or 4, and in this event the load will be transmitted to both rail sections. Assuming that a wheel rests entirely upon a head 1 (Fig. III), it is apparent that the load will be transmitted through the vertical web 3, but it will also be transmitted through the rib 75 7 and vertical web 6 of the other rail section. If the wheel rests entirely upon the head 4, the load will be transmitted from the web 6 to the rib 8 which rests upon the other rail section. In either event, the load will 80 be sustained by the cooperative action of both rail sections, and both of the base flanges 2 and 5 will be forced into firm engagement with the abutments 10 and 11 between which they are confined. 85

I claim:

1. A sectional rail comprising a pair of mating rail sections each having a head at the top, a base flange at the bottom and a web uniting said head and base flange, the bottom faces of said base flanges being inclined outwardly and downwardly toward the outer margins of the rail sections, a flat supporting plate on which the outer margins of said base flanges are seated, the inclined bottom faces of said base flanges being separated from said flat supporting plate at points between said outer margins, and abutments on said supporting plate engaging said outer margins of the base 100 flanges to receive the lateral thrusts resulting from a load on said rail sections, one of said rail sections having its head extended over and seated on the head of the other rail section, the rail section having said extended head also having its base flange extended in the form of a rib projecting toward the other section, and the last mentioned section having a longitudinal rib overlapping and seated upon the first mentioned rib, said base flanges being confined between said abutments so that a downward thrust on either rail section will result in lateral thrusts at both of said abutments. 115

2. A sectional rail comprising a pair of mating rail sections each having inclined faces extending from one of its sides, the inclined faces of one of said rail sections being wedged onto the inclined faces of the other section, and the adjacent side faces 120 of said sections being otherwise separated from each other to permit firm contact at said inclined faces. 125

3. A sectional rail comprising a pair of mating rail sections each having a head and 130

a base flange extending from its outer side and inclined faces extending from its inner side, the inclined faces of one of said sections being arranged between and wedged 5 onto the inclined faces of the other section, and the inner sides of said sections being otherwise separated from each other to permit firm contact at said inclined faces.

4. A sectional rail comprising a pair of 10 mating rail sections each having inclined faces extending from one of its sides, the inclined faces of one of said rail sections being wedged onto the inclined faces of the other section, the adjacent side faces of said 15 sections being otherwise separated from each other to permit firm contact at said inclined faces, each of said rail sections having a base flange at its outer side, a support on which the outer margins of the base flanges are seated, 20 said base flanges being separated from said support at points between said outer margins, and abutments on said support engaging said outer margins to receive the lateral thrusts resulting from a load on said 25 rail sections.

5. A sectional rail comprising a pair of mating rail sections each having a head and a base flange extending from its outer side and inclined faces extending from its inner side, the inclined faces of one of said sections being arranged between and wedged 30 onto the inclined faces of the other section, and the inner sides of said sections being otherwise separated from each other to per-

mit firm contact at said inclined faces, a support 35 on which the outer margins of said base flanges are seated, said base flanges being separated from said support at points between said outer margins, and abutments extending upwardly from said support and 40 engaging said outer margins to receive the lateral thrusts resulting from a downward thrust on either of said rail sections.

6. A sectional rail comprising a pair of mating rail sections each having a head at 45 the top, a base flange at the bottom and a web uniting said head and base flange, the base flanges being extended outwardly from the webs of the respective rail sections, and a support 50 on which the outer margins of said base flanges are seated, said base flanges being separated from said support at points between said outer margins, and abutments on said support engaging the outer margins of said base flanges to receive the lateral thrusts resulting from a load on said rail sections, said base flanges being confined between said abutments, and the adjacent inner faces of said pair of rail sections being provided with interlocking 55 projections arranged one above the other and in direct contact with each other so that a downward thrust on either rail section will result in lateral thrusts at both of said abutments. 60

In testimony that I claim the foregoing I hereunto affix my signature.

HENRY F. MERKER.
